PIPE LINE CLEANER

Arthur H. Rincey and Louis J. Weber, Bartlesville,
Okla., assignors to Phillips Petroleum Company,
a corporation of Delaware

Application June 5, 1939, Serial No. 277,507

9 Claims. (Cl. 15—104.06)

This invention relates to a device for cleaning the interior wall of a pipe line or similar conduit. In its more specific aspects our invention is adapted to remove accumulated deposits and films from the inside of piping which is employed to transport various fluids, including crude and treated petroleum liquids.

In the course of conveying certain liquids, such as crude oil and other hydrocarbon products, through a pipe line, paraffin and other undesirable materials are deposited on the inner wall of the piping. The substances so deposited will gradually build up until they will eventually not only restrict and reduce flow, but will also contaminate slugs of different fluids that may be passed through the line. If it is desired to use the same pipe line to carry a quantity of white gasoline or like product, the deposits of paraffin must be completely removed, otherwise the gasoline will become tainted. A gasoline which has been contaminated in this manner cannot be used but must first be reprocessed at the receiving end of the pipe line in order to extract the adulterating components. This is obviously an expensive procedure, as it necessitates a costly duplication of equipment and effort.

Numerous attempts have been made to rectify this condition by means of mechanical devices which are passed through the line to scrape off the deposits on the pipe wall, thus lowering the frictional resistance to flow. By the use of conventional types of scrapers, pipe lines may now be kept free from thick deposits which tend to hinder flow. On the other hand, experience has proven that these devices do not completely clean the interior wall of the piping as they allow films of the objectionable substances to remain on the inner surface of the piping. These films are as undesirable as thick deposits from the viewpoint of contamination and must be removed before a second fluid can be transported without danger of adulteration. One method of removing these films is by running a slug of a suitable cleansing solution through line to dissolve and carry away the undesirable coating. In this manner the piping may be reconditioned to some extent, but this method is neither economical nor dependable in most cases.

Our invention contemplates a pipe line cleaner which obviates the difficulties experienced in the past, and is adapted to perform its functions in a highly satisfactory manner. The instant invention basically consists of a series of flexible discs, preferably composed of some form of natural or synthetic rubber, and wire brushes,

all of which are constructed and arranged into a unitary assembly. Means are provided to impart a rotary motion to one of the brushes with the result that it will vigorously scour the inner surface of the pipe line and in that way remove either heavy or thin films. A series of spaced baffles intermediate the ends of our cleaner are designed slightly smaller in diameter than the internal diameter of the piping. The fluid which 5 propels the cleaner through the pipe line will attain a higher velocity as it passes through the annular region between these baffles and the pipe walls, thereby creating additional scouring action. In the practice of our invention we recommend the use of gasoline as the propelling fluid as it is a good solvent for paraffin. Therefore, by means of the solvent effect and high velocity of the gasoline between the baffles and the pipe wall and by virtue of the scouring and 10 scrubbing action of the rotating brush, we are able to more thoroughly clean a pipe line than has been possible heretofore. When deposits inside a line have been permitted to build up to an appreciable extent, the best results can be obtained by first passing the usual type of scraper 15 therethrough in order to remove the major portion of the material and then employing our cleaner to remove the remaining comparatively thin coating.

15 It is the primary object of this invention to remove material which is deposited on the inside wall of piping in the course of normal service.

Another object of our present invention is to 20 thoroughly remove comparatively thin films of undesirable substances from the interior of a pipe line or similar conduit system.

25 The present invention has for a further object the provision of a pipe line cleaning device which is simple and compact in design, rugged in construction and inexpensive to manufacture.

30 These and additional objects and advantages 30 will be apparent to those skilled in the art by reference to the following detailed description and annexed drawing which represents a longitudinal cross section view through the center of 35 a preferred embodiment of the invention. The device of this invention is depicted in the drawing as having its major portion disposed in a pipe 10 and moving therethrough in the direction 40 of the arrow, with the rear cleaning elements in close contact with the internal surface of the pipe and a valve mechanism in full open position.

45 Referring to the drawing, we have denoted 50 therein a section of pipe 10 which is to be cleaned

by our device. Inside the pipe is a central body consisting of a tubular member 11 and a shaft 12 which are rigidly connected at 13 by welding or some other known method. Mounted near each end of the central body is a pair of flexible wiping discs 14, which are made of rubber or any like substance, and a wire brush 15. It will be noted that the peripheral surfaces of the flexible discs are frustro-conical in shape; and, also that the forward discs are provided with one or more fluid passageways 16. Through the co-operation of nuts 17 and 18 and back-up plates 19, 20 and 21, the corresponding disc and brush assemblies are maintained in proper position on the central body. Truncated cone shaped baffles 22 are attached to tubular member 11 and are designed so that the diameter of the larger end is somewhat smaller than the internal diameter of the pipe.

The open end of tubular member 11 is beveled inwardly at 23 to serve as a valve seat for a valve 24 which is removably attached to one end of a valve stem 25 through the coaction of a shoulder 26, a metal ring 27 and a nut 28. The other end of the valve stem is slidably supported in a flanged sleeve 29 which is in threaded engagement with a partition 30. This partition is threadedly connected to the inside wall of the tubular member and is provided with a series of fluid ducts 31. An externally threaded annular ring 32, having an opening 33 to receive an actuating wrench (not shown), locks the partition in the desired position. Referring back to the valve, it is seen that it is normally maintained in open position by a compression spring 34 which is concentrically arranged with respect to the stem between a flange 35 and sleeve 29. When valve 24 is fully open, its relative position with respect to its seat 23 may be readily altered by merely adjusting sleeve 29, partition 30, or both. An end nut 36 is employed to vary the force exerted by compression spring 34. By virtue of the above described construction, it is evident that our valve has a wide range of adjustability. A series of fluid ports 37 establishes communication with the interior of the tubular member and annular space 38.

A cylindrical sleeve 39, concentric with shaft 12, is free to rotate on bearings 40. One end of this sleeve bears against a frictionless ring 41 while the other end bears against plate 21. A wire brush 42 is mounted on this sleeve between a fixed back-up plate 43 and a removable back-up plate 44 which is held against the brush by a nut 45. A plurality of spring arms 46 are affixed to sleeve 39 and are forked at their ends 47 to receive rollers 48 which are journaled upon pins 49. The periphery of each roller is serrated as indicated by reference numeral 50 in order to afford greater traction when pressed against the inner surface of the pipe. With the axes of the rollers disposed at an angle to the direction of movement of our cleaner through the pipe line, a rotary motion is imparted to sleeve 39 and brush 42 during the cleaning procedure.

For the purpose of outlining the operation of the instant invention, let us first assume that only a comparatively thin layer or accumulation of the contaminating material is present in the pipe. Our cleaner is inserted in the pipe and is propelled by a suitable "slug" of liquid, preferably gasoline under pressure, in the direction indicated by the arrow in the drawing. The principle of operation of our cleaner is based on a combined wiping, washing and cross brushing 75

of the pipe walls. During the passage of our device through pipe 10, the forward assembly of flexible discs 14 and brush 15 tends to wipe off and brush some of the deposits. Through the cooperation of rollers 48 and sleeve 39, brush 42 is caused to rotate and thoroughly scrub the inside of the pipe. It is evident that while the wiping and brushing action of the forward and rear disc and brush assemblies is in the direction of the axis of the pipe, brush 42 revolves about the pipe axis, thus assuring more thorough cleaning. A portion of the propelling fluid normally flows by valve 24, into tubular member 11, through ports 37 and thence into annular space 38. This part of the fluid exerts a pressure on the baffles 22; and, in passing between the larger end of each baffle and the pipe, the velocity of the fluid will be increased, thereby creating a washing action on the pipe wall. The fluid then passes through brush 42, fluid passages 16 and front brush 15. The material which is removed from the pipe wall is carried through and beyond our device by the fluid, and collections of material will not be collected either inside or directly in front of the cleaner.

The rate of travel of the cleaner through the pipe is dependent upon the internal diameter of tubular member 11 and the number and size of ducts 31 and ports 37. The slower the cleaner moves with respect to the velocity of the fluid, the more fluid must pass therethrough. Conversely, if less fluid passes through the cleaner, the cleaner will travel faster in the piping. The valve arrangement is employed to insure a predetermined rate of travel and to prevent the device from becoming stuck in the line. Should movement of the cleaner become hindered by an obstruction, such as a thick layer of deposit, the pressure of the fluid will partially or completely close valve 24 against the action of spring 34. Consequently, less fluid enters tubular member 11 resulting in a greater pressure drop across the cleaner and an increase in pressure on the back end of the cleaner. This increased pressure on the back end of our device will urge the same past the obstruction, at which time the valve will reopen and the cleaner will again function in a normal manner.

From the foregoing it is believed that the construction, operation and advantages of our present invention will be readily comprehended by persons skilled in the art. It is to be clearly understood, however, that the form of our invention herewith shown and described is to be taken as a preferred example of the same and that various changes in the shape, size and arrangement of parts may be resorted to without departing from the spirit of our invention as defined by the appended claims.

1. A fluid propelled pipe cleaning device comprising a central body including a tubular member; cleaning means including an impervious piston connected to the central body; a normally open valve associated with the tubular member; and means responsive to a predetermined rise in pressure behind the piston for actuating the valve to close the same.

2. A fluid propelled pipe cleaning device comprising a central body including a tubular member; a valve associated with the tubular member; spring urged means for normally maintaining the valve in open position; said means being responsive to fluid pressure to close the valve and control the flow of fluid therethrough; and

cleaning means including an impervious piston connected to the central body.

3. A fluid propelled pipe cleaning device comprising a central body including a tubular member; cleaning means including an impervious piston connected to the central body; cleaning means rotatably connected to the central body; a normally open valve associated with the tubular member; and means responsive to a predetermined rise in pressure behind the piston for actuating the valve to close the same.

4. A fluid propelled pipe cleaning device comprising a central body including a tubular member; a valve associated with the tubular member; spring urged means for normally maintaining the valve in open position; said means being responsive to fluid pressure to close the valve and control the flow of fluid therethrough; cleaning means including an impervious piston fixedly connected to the central body; and cleaning means rotatably connected to the central body.

5. A fluid propelled pipe cleaning device comprising a central body including a tubular member; a pair of cleaning means connected to the central body, at least one of the cleaning means including an impervious piston; a baffle on the central body intermediate the cleaning means; a passage in the tubular member for transmitting fluid from one end of the central body to the baffle; a normally open valve associated with the tubular member; and means responsive to a predetermined rise in pressure behind the piston for actuating the valve to close the passage.

6. A fluid propelled pipe cleaning device comprising a central body including a tubular member; a pair of cleaning means fixedly connected to the central body, each cleaning means including a pair of wiping discs and a brush mounted therebetween; a baffle on the central body intermediate the cleaning means; a passage in the tubular member by-passing one of the pair of wiping discs; normally open valve means connected to the tubular member, said valve means being adapted to close the passage upon rise in pressure behind the discs; and cleaning means rotatably connected to the central body.

7. A fluid propelled pipe cleaning device comprising a central body including a tubular member and a shaft member; a pair of cleaning means fixedly connected to the central body, each cleaning means including a pair of wiping discs

and a brush mounted therebetween; a baffle on the central body intermediate the cleaning means; a passage in the tubular member for transmitting fluid from one end of the central body to the baffle; a normally open valve associated with the tubular member; means responsive to fluid pressure for closing the valve to control the passage of fluid therethrough; and cleaning means rotatably mounted on the shaft member, said last mentioned means including a sleeve rotatably mounted on the shaft, a brush attached to the sleeve and a plurality of rollers inclined with relation to the axis of the pipe for cooperating with the sleeve and the interior wall of the pipe to impart rotary motion to the brush which is attached to the sleeve.

8. A liquid actuated pipe cleaning device comprising a central body; a driving piston connected to the central body and adapted to engage the inner wall of a pipe in which the device is used; a passage for by-passing a portion of the actuating liquid past the piston; baffle means associated with the central body for directing the by-passed liquid toward the pipe wall to obtain a flushing action; a valve in the passage; spring urged means for normally maintaining the valve in open position; said valve being adapted to close the passage upon rise in pressure behind the piston if the movement of the device through the pipe is stopped by an obstruction; and cleaning means connected to the central body.

9. A liquid actuated pipe cleaning device comprising a central body; a driving piston connected to the central body and adapted to engage the inner wall of a pipe in which the device is used; a passage for by-passing a portion of the actuating liquid past the piston; baffle means associated with the central body for directing the by-passed liquid toward the pipe wall to obtain a flushing action; a valve in the passage; spring urged means for normally maintaining the valve in open position; said valve being adapted to close the passage upon rise in pressure behind the piston if the movement of the device through the pipe is stopped by an obstruction; cleaning means fixedly connected to the central body; and cleaning means rotatably connected to the central body.
